SAW-TOOTH WAVE GENERATOR

Simeon I. Tourshou, Philadelphia, Pa., assignor
to Radio Corporation of America, a corporation
of Delaware

Application September 27, 1947, Serial No. 776,465

3 Claims. (Cl. 250—36)

1

The present invention relates to generators for producing non-sinusoidal waves, and more particularly, but not necessarily exclusively, to such generators for producing waves substantially of sawtooth form.

Where a beam of electrons is generated and directed against a target electrode, some means is normally provided for causing deflection of this cathode ray beam in two different directions in order that the cathode ray beam may be caused to scan or traverse the desired portion of the target electrode. In a television camera or receiver, the electron beam is deflected at a slow speed, usually in the vertical direction, and at a high speed, usually in the horizontal direction. The high speed deflection provides line scanning and the low speed deflection provides field or frame scanning. In oscilloscopic devices, the cathode ray beam is usually deflected horizontally at a predetermined rate, while the beam is deflected vertically in accordance with the potential variation to be observed. In these instances of beam deflection, it is generally desirable that the cathode ray beam be deflected uniformly with respect to time, and accordingly, some means must be provided for producing deflection voltages. Since it is desired that the beam be deflected uniformly with respect to time, the applied deflection voltage must appear approximately as a sawtooth wave form or be of such shape as to produce a current of sawtooth wave form in an inductance. In accordance with this invention, a recurring sawtooth of voltage, suitable for slow speed or high speed scanning, is produced by a novel oscillator which is generally of the type referred to as a "blocking oscillator." The oscillator provided by the invention employs a relatively low cost transformer which may be a single tapped air core coil. The coil, therefore, functions as an air core autotransformer. A powdered iron core may be used, if desired, but operation may be had without employing a metallic core of any kind. As will be pointed out hereinafter, the iron core, if it is used, may be movable so that its position in the core may be varied to control the free running speed of the oscillator.

An object of this invention is to provide a sawtooth wave generator consisting of simple parts so that it is cheap to manufacture.

Another object is to provide a sawtooth wave generator which does not require a transformer having a laminated iron core and separate primary and secondary windings.

A further object of the invention is to provide a sawtooth wave generator, the free running

speed of which may be controlled in a novel manner by providing means for changing the inductance of a coil.

Other objects and advantages of the present invention will, of course, become apparent and immediately suggest themselves to those skilled in the art to which the invention is directed from a reading of the following specification in connection with the accompanying drawings in

10 which:

Fig. 1 is a diagrammatic illustration of a sawtooth wave generator embodying the invention;

Fig. 2 shows a series of curves;

Fig. 3 shows a curve obtained during operation 15 of the generator with a different degree of damping;

Fig. 4 shows a modification of the generator of Figure 1; and

Fig. 5 shows a further form which is preferred 20 for certain applications.

Referring now to the drawing, and for the present to Fig. 1 thereof, there is shown a single coil 12, which may be regarded as an autotransformer having a secondary or grid section 14 and 25 a primary or plate section 16. The plate section 16 is connected to the anode 18 of a discharge tube, such as the three electrode vacuum tube 19. The grid 21 of this tube is connected through a capacitance 23 to the end of the grid section 14. Synchronizing impulses, such as television 30 sync signals, usually in the form of timed recurring pulses 26, are fed into the cathode 28 of the tube 19. The cathode is returned to ground by way of an unbypassed resistor 31.

A capacitance 32 is connected to a suitable 35 source of positive potential (not shown), which may be connected to a terminal 33 through resistors 36 and 37 in series. Under certain conditions of operation of the generator of this invention, the capacitance 32 is charged through

40 the resistors 37 and 36. Discharge, or partial discharge, of this capacitance is brought about by a sync pulse 26, which initiates an oscillation slightly before the would-be free-running oscillation which, as the grid swings positive, dis- 45 charges or partly discharges the capacitance 32. A resistor 38 serves as a damping resistor, and in Fig. 1 it is shown as being connected across the entire autotransformer coil 12. This resistor may be connected across any portion of the winding.

The output voltage of sawtooth wave form is taken from the resistor 36, which serves as a potentiometer having a movable contact 41. With the potentiometer connection shown, the frequency of oscillation of the generator is independent of the setting. A change in position

of the contact 41 provides for variable "high peaking" so that the output wave may have a variable impulse part.

In the operation of the arrangement of Figure 1, the capacitance 32 is charged through the resistors 36 and 37 in series, the charge curve 44 (Fig. 2) being substantially linear, initially. The sync pulses 26, shown as extending in the positive direction in Fig. 2 for convenience, bring about an abrupt discharge of the capacitance 32 as represented at 46. The resistor 36, which is in the discharge path of the capacitance, as well as in its charging path, has the function of providing the pulse portion 48 of the wave, since the capacitance 32 cannot be completely discharged due to the time constant of the capacitance 32 and the resistor 36 as well as the plate resistance of the tube. When the tube 19 is blocked, as will be explained hereinafter, the plate voltage does not have to rise slowly from the cathode potential, but instead rises immediately to an appreciable value, due to the charge that remains on the capacitance 32. The plate voltage then slowly rises along the curve 44 which, as indicated, is substantially linear. Upon the occurrence of a sync pulse 26, the grid voltage is raised immediately and increases in the positive direction due to transformer action, as indicated at 51 (Fig. 2). Following this, the grid is driven abruptly negative when the capacitance 32 is nearly discharged and a negative charge is stored in the capacitance 23, which leaks off as represented by the portion of the curve designated 52.

The negative condition of the grid, which is assumed abruptly, as stated, is a result of several factors, the discharge of the capacitance 32 being only one of these factors. The principal reason for the grid going negative is the oscillatory circuit comprising the inductance and distributed capacity of the coil 12, as well as the tube and stray capacity of the circuit, so that having reached the positive peak, the voltage starts decreasing and then swings negative, tending to follow a damped sine wave. The second reason is the collapse of the plate current which induces a voltage in the coil tending to accelerate the negative swing and even making it greater than positive. The third is the negative charge stored in the capacitance 23.

The discharge of the capacitance 23 occurs through a grid resistor 53 in series with an adjustable resistor 54. The time of discharge can be regulated by varying the resistance of the resistor 54. Just before the conduction point of the tube is reached, the occurrence of the next successive sync pulse 26 causes the cycle to be repeated. Fig. 3 of the drawings shows the wave form when the degree of damping, which is determined by the resistor 38, is less.

Fig. 4 of the drawings shows a slightly modified arrangement of the apparatus of Figure 1 in which the damping resistor, designated 38a, bridges the plate section 16a of the coil, rather than the entire coil, as shown in Fig. 1. The damping resistor 38a may be connected across any portion of the winding. A core 56 is also indicated, which may be of powdered and compressed ferrous material. Also, in Fig. 4, an arrangement is illustrated whereby the sync pulses 26 are applied in the positive direction to the grid 21a of the tube 19a.

Fig. 5 of the drawings shows a further modification of the arrangement of Fig. 1 in which the sync input is supplied to an auxiliary wind-

ing 58, which is coupled to the main winding 12b. The direction of winding of the auxiliary coil 58, or the connection of the sync input to the terminals 61 takes care of the polarity of the applied sync signal. An adjustable core 62 is mounted in any suitable manner (not shown) so that it may be moved into or out of the coil, somewhat like the tuning inductance on a radio receiver. This change in inductance changes the resonant frequency and the impedance of the circuit, as well as the coupling between the plate and grid sections of the winding, and through any one, or any combination of these changes, varies the peak voltage developed on the grid, as well as the plate. The frequency of oscillation is varied since the charge on the capacitance is varied and the time for this charge to leak off is varied. This method of control eliminates the cost of the variable resistor 54 of Fig. 1.

The windings 12, 12a and 12b are preferably of the universal type with low distributed capacity with parameters essentially independent of voltage. In general, this coil is more stable than the laminated iron core transformer. When the universal type of coil is connected as an autotransformer, it maintains the ratio of plate current to grid current in the positive grid region. The frequency is a function of this ratio. By making the amplitude of oscillations and therefore the average bias developed by oscillations, large enough, the effect of variation of the contact potential of the tube is minimized.

Having now described the invention what is claimed and desired to be secured by Letters Patent is the following:

1. A blocking oscillator comprising a vacuum tube having a control grid, a plate and a cathode, an autotransformer comprising two inductively coupled coil sections, one of said coil sections being connected directly to the plate of said tube, a capacitor, a connection from the other of said coil sections to said grid through said capacitor, means including a resistor connected to the junction of said coil sections to maintain said plate positive with respect to said cathode, a second capacitor connected to the junction of said coil sections, said second capacitor also being effectively connected to the point of connection of the cathode in said oscillator, said second capacitor being charged from said positive potential applying means and being discharged by said tube upon occurrence of a pulse of grid voltage, and a damping resistor connected across at least a part of said autotransformer.

2. The oscillator of claim 1, wherein said coil sections consist of windings having low distributed capacity.

3. A blocking oscillator comprising a vacuum tube having a control grid, a plate and a cathode, an autotransformer comprising two inductively coupled coil sections, one of said coil sections being connected directly to the plate of said tube, a capacitor, a connection from the other of said coil sections to said grid through said capacitor, means including a resistor connected to the junction of said coil sections to maintain said plate positive with respect to said cathode, a second capacitor connected to the junction of said coil sections through a second resistor, said second capacitor also being effectively connected to the point of connection of the cathode in said oscillator, said second capacitor being charged from said positive potential applying means and being discharged by said tube upon occurrence of a

pulse of grid voltage, and means for obtaining an output wave having a variable pulse component from said oscillator, said means comprising a connection to said second resistor which is adjustable along said second resistor.
